WASHING MACHINE

John Zimarik, Akron, Ohio

Application November 23, 1938, Serial No. 241,987

8 Claims. (Cl. 68—58)

This invention relates to washing machines. An object of the invention is to provide a washing machine of the tumbler-drum type in which the use of the usual external liquid-containing shell around the clothes-containing drum is obviated, and in which wash-water or other fluid treating material may be supplied to or emptied from the drum while the drum is either rotating or stationary, the filling and emptying being accomplished from one side of the drum thereby to leave the other side of the drum unobstructed for loading and removing the laundry.

Another object of the invention is to provide in a washing machine of the tumbler-drum type means for rapidly and effectively emptying the drum while the same is rotating, said means including valve mechanism which is unaffected by rotation of the drum.

Another object of the invention is to provide a washing machine of the character disclosed having means for recovering fluid which may otherwise leak past the bearing and journal of the rotatable drum.

Still another object of the invention is to provide in a washing machine of the character disclosed a safety escape for accumulated steam pressure therein.

These and other objects will be manifest from the following brief description and the accompanying drawings.

Of the accompanying drawings:

Figure 1 is a side elevation, partly broken away and in section, of a washing machine embodying the invention.

Figure 2 is a cross-section on line 2—2 of Figure 1.

Referring to the drawings, the numeral 10 designates a suitable base having a back-plate 11 secured thereto for supporting a bearing bracket 12. Bracket 12 may be provided with an annular bearing sleeve 13 upon which may be journaled drum 14. Rollers 15, 15, in brackets 16, 16 mounted on base 10, may be arranged to engage and rotatably support the drum 14 intermediate the sides thereof, thereby leaving the front side of the drum free and unobstructed for loading and unloading laundry to and from the washer through a suitable removable cover-plate 11.

For rotatably driving the drum 14 the rear marginal edge thereof may be provided with annular V-grooves 18, 18 for engagement of V-belts 19, 19 driven, through a pulley 20 on a shaft 21, by a suitable reduction gearing 22 and

motor 23 supported on bearing bracket 12. Motor 23 may be of the reversing type and suitable mechanism (not shown) may be provided in association therewith to reverse the drum 14 in alternate directions at periodic intervals.

Drum 14 preferably is provided with a washing or treating chamber 24 at the front side of the washer and a liquid emptying compartment 25 at the rear thereof, the chamber 24 being separated from compartment 25 by a partition 26, which may be flanged at 27 to rotatably engage the outer periphery of an annular sleeve 28 interiorly concentric with sleeve 13. The inner end of sleeve 28 may be closed by means of a plate 29 secured thereto and an annular retaining ring 30 may be secured on plate 29 adapted to slidably engage partition 26 to retain the drum 14 against lateral movement on bearing-bracket 12. The inside diameter of sleeve 28 may be relatively large and yet provide a sufficiently large annular space in emptying compartment 25, thus making it possible to provide a suitable opening 31 in plate 29 at the top of the drum and well above the normal water or load line of the washer. Opening 31 provides efficient means for steam accumulated in chamber 24 to vent to the exterior of the drum, thereby minimizing the possibility of blowing off the cover 11 or otherwise causing injury or damage.

The treating chamber 24 preferably has provided on the inner periphery thereof hollow tumbler ribs 32, 32 perforated at 33, 33 to permit drainage and circulation of fluid through the ribs, the rear end of the latter opening into the emptying compartment 25 at 25a, 25a. The ribs 32 may have funnel-shaped interiors diverging toward the rear side of the drum for impelling the liquid from the treating chamber into the emptying compartment as the drum is rotated in one direction, thereby to rapidly empty the drum. There also may be provided on the inner periphery of chamber 24 additional angularly or helically arranged hollow perforated vanes 34 extending to the partition 26. Vanes 34 communicate with compartment 25 at 35, 35 to permit drainage and circulation of fluid to the emptying compartment and to impel said fluid into the compartment as the drum is rotated to thereby aid in rapidly draining the drum. The ribs 32 and vanes 34 preferably are arranged alternately to impel the contents of the chamber toward the emptying compartment as the drum is rotated in reversed directions. Vanes 34 serve also to shift the contents of treating chamber laterally back and forth as the

drum 14 is alternately rotated in reversed directions. The features and arrangement of the ribs 32 and vanes 34 are described in detail in the co-pending application of John Zimark for Letters Patent for improvements in Washing machines, Serial No. 218,803, of which this application is a continuation in part.

Wash water, rinse water, bluing, soap solution, or other treating materials may be supplied to the washer, through suitable piping 37 threaded into sleeve 28 to communicate with emptying chamber 25, the latter in turn communicating with treating chamber 24 through the perforated ribs 32 and perforated vanes 34. Mounted on bearing-bracket 12 adjacent the bottom of compartment 25 may be a suitable drain valve, subsequently to be described, operable to empty the chamber 24 while the drum is rotating or stationary.

As a provision against leakage of treating fluid at the inner edge of sleeve 13 and past the bearing connection between drum 14 and sleeve 13, the drum 14 may be enlarged at 38 to provide an annular pocket 39 intermediate said inner edge of sleeve 13 and the rear marginal edge of drum 14. Pocket 39 may communicate with chamber 25 through a relatively small opening 13a in bearing sleeve 13 at the top of drum 14 and preferably there is provided a series of radial vanes 40, 40, arranged to rotate with the drum 30 and thereby lift fluid which has leaked into pocket 39 up to the top of compartment 25, where the fluid is dropped by gravity through opening 13a and into said compartment to be either retained therein or drained through a valve 41.

Valve 41 (see Figure 1) preferably is of the flapper type, carried by a downwardly extending arm 42 secured on a shaft 43 rotatably mounted in lugs 44 on bearing bracket 12. The valve 41 is beveled at 45 to seat in a beveled end portion of a sleeve 46, the latter opening into chamber 25. A spring 47 normally urges the valve into closed position. An upwardly extending arm 48 secured on shaft 43 may have a rod 49, attached to the free end thereof, extending to the front of the machine for controlling the opening and closing of the valve at will against the yielding action of spring 47.

In the use of the machine for washing or treating clothes, the clothes are placed in chamber 24 through the opening at the front of the drum, after removing cover 17 thereof. With valve 41 closed and cover 17 back in place on the drum, water together with soap, bluing, etc. may be supplied through piping 37, compartment 25 and through perforated ribs 32 and vanes 34 to treating chamber 24. As the drum is alternately rotated in reversed directions the vanes 34 will shift the wash load back and forth in chamber 24 thoroughly to agitate the clothes, and the treating fluid, by reason of the construction of said vanes and the ribs 32, will be constantly circulated through the drum. Any fluid leaking outwardly past the inner edge of bearing sleeve 13 will be picked up by vanes 40 and pumped back in to the emptying compartment. Should hot water be used for washing, any accumulation of steam arising therefrom to the top of the drum will vent through the opening 31 in plate 29. The wash water may be thoroughly emptied or expelled from the drum either while the latter is rotating or stationary, by opening the valve 41. Rinse water, or other treating fluid, may be supplied to the drum while the

latter is rotating or stationary, with valve 41 open or closed.

Modifications of the invention may be resorted to without departing from the spirit thereof or the scope of the appended claims.

What is claimed is:

1. A machine of the character described comprising a drum rotatable about a substantially horizontal axis, said drum having a treating chamber, a bearing member for rotatably supporting said drum, said member having a liquid supplying and emptying compartment in communication with said chamber, means on said drum operable by rotation thereof for retrieving liquid which may leak outwardly between the bearing surfaces of said drum and said bearing member and pumping said liquid back into said compartment, and a valve on said member in communication with said compartment operable at will to drain said drum while said drum is rotating or stationary.

2. A machine of the character described comprising a single-shell drum rotatable about a substantially horizontal axis, said drum having a treating chamber for containing a determinate quantity of liquid, a stationary bearing member for rotatably supporting said drum at one side thereof, said member having a liquid supplying and emptying compartment therein communicating directly with said chamber while the drum is rotating or stationary, means in said chamber operable by rotation of said drum for ejecting the liquid from said chamber into said compartment, and valve means on said member operable at will to drain the liquid from said chamber by gravity through said communicating compartment while said drum is rotating or stationary.

3. A machine of the character described comprising a drum rotatable about a substantially horizontal axis, said drum having a treating chamber, a bearing member for rotatably supporting said drum, said member having a supplying and emptying compartment therein communicating with said chamber, means in said chamber operable by rotation of said drum for ejecting the liquid from said chamber into said compartment, means on said drum operable by rotation thereof for retrieving liquid which may leak outwardly between the bearing surfaces of said drum and said bearing member and pumping said liquid back into said compartment, and means on said member operable at will to drain said drum by gravity while said drum is rotating or stationary.

4. A machine of the character described comprising a drum rotatable about a substantially horizontal axis, said drum having a treating chamber, a hollow bearing member adapted to have said drum journaled thereon, said member cooperating with said drum to provide an annular liquid supplying and emptying compartment at one side of the drum in communication with said chamber, means on said drum operable by rotation thereof for retrieving liquid which may leak outwardly between the bearing surfaces of said drum and said bearing member and pumping said liquid back into said compartment, and a valve operable at will to drain liquid from said drum by gravity while the drum is rotating or stationary.

5. A machine of the character described comprising a single-shell drum rotatable about a substantially horizontal axis, said drum having a treating chamber adapted solely to contain a de-

eterminate quantity of liquid, a stationary bearing member for rotatably supporting said drum at one side axially thereof, said member having therein a liquid supplying and emptying compartment in fluid sealing relation with said drum, said drum being apertured to communicate said chamber directly with said compartment in all rotated positions of the drum, and a valve on said stationary member in communication with said compartment and operable at will to drain liquid from said chamber through said compartment while said drum is rotating or stationary.

6. A machine of the character described comprising a single-shell drum having a treating chamber for containing treating liquid, said drum being rotatable about a substantially horizontal axis, a stationary member for rotatably supporting said drum at one side thereof, the other side of the drum extending free and unobstructed by supporting structure, said member having a passage communicating with said chamber in all rotated positions of the drum, and valve means in said stationary member operable at will for draining said chamber through said communicating passage while the drum is rotating about its axis or stationary.

7. A machine of the character described comprising a single-shell drum rotatable about a substantially horizontal axis, said drum having a treating chamber adapted solely to contain a determinate quantity of liquid, a stationary bearing member for rotatably supporting said drum at

one side axially thereof, said member having therein a liquid supplying and emptying compartment in fluid sealing relation with said rotatable drum, said drum being apertured to communicate said chamber directly with said compartment in all rotated positions of the drum, and a valve on said stationary member operable at will to drain liquid from said chamber through said compartment communicating therewith, said valve being located with respect to the bottom of the drum whereby it is operable to drain the liquid from said chamber by gravity while the drum is rotating or stationary.

8. A machine of the character described comprising a drum rotatable about a substantially horizontal axis, said drum having a treating chamber for containing a liquid, a hollow bearing member for rotatably mounting said drum thereon, the hollow portion of said member providing an annular liquid supplying and emptying compartment at one side of the drum in communication with said chamber in all rotated positions of the drum, said bearing member having means providing an orifice above the liquid level of said chamber and communicating the interior of said chamber with the exterior for venting volatile gases from the chamber, and a valve on said member operable at will to drain liquid from said drum through said compartment by gravity while the drum is rotating or stationary.

JOHN ZIMARIK.
